UNITED STATES PATENT OFFICE.

CHARLES H. MATTHEWS AND JAY E. MATTHEWS, OF DRESDEN, KANSAS.

MEANS FOR SPLICING AND STRETCHING FENCE-WIRES.

1,307,409.

Specification of Letters Patent. Patented June 24, 1919.

Application filed August 22, 1918. Serial No. 250,998.

To all whom it may concern:

Be it known that we, CHARLES H. MATTHEWS and JAY E. MATTHEWS, citizens of the United States, residing at Dresden, in the county of Decatur and State of Kansas, have invented certain new and useful Improvements in Means for Splicing and Stretching Fence-Wires, of which the following is a specification.

10 The object of our invention is to facilitate the splicing of broken fence wires and the joining of either barbed or plain wires. The invention also seeks to attain the desired end by the employment of a tool which will 15 be inexpensive to construct and easily operated to efficiently perform all the steps in the splicing of the wire.

The stated objects and such other incidental objects as will hereinafter appear are 20 attained in such a tool as is illustrated in the accompanying drawings and in the depicted manipulation of the same, all of which will be hereinafter fully set forth.

In the drawings—

25 Figure 1 is a perspective view of a tool constructed in accordance with and adapted to carry out our invention;

Fig. 2 is an end elevation of the same;

Fig. 3 is a plan view thereof; and

30 Figs. 4 to 10 are detail views of a somewhat diagrammatic nature, showing the different steps in the manipulation of the tool to splice a broken wire.

The tool or implement shown in the drawings and embodying our invention comprises a flat plate or main body 1 which is preferably of metal in order to possess the required strength without being bulky or heavy and which is provided in one side 35 with a central longitudinal groove 2, as shown, the said groove being conveniently produced by forming a bead extending lengthwise of the plate. To one end of this plate, we secure a spike or foot 3 which is 40 adapted to enter the ground and support the implement in the position where it is to be used. This spike or foot is provided with a lateral arm or tailpiece 4 which extends approximately parallel with and in the same 45 direction as the lower end of the plate 1 in spaced relation thereto, said tailpiece being dished or curved, as shown at 5, whereby it will project rearwardly from the plane of the main plate or body 1, as shown most 50 clearly in Fig. 3. At its upper end, the main

plate or body is provided with forwardly projecting ears or bearings 6 in which a drum 7 is journaled and at one side is provided with a lateral arm or bracket 8 having its extremity bent forward to form a rest 60 upon which the length of wire is supported in the operation of the tool as will presently more fully appear. Pivoted near the inner extremity of the rest 9 is a locking arm or lever 10 which is adapted to extend 65 over the rest and project beyond the front end of the same, being equipped with a retaining loop 11 which is adapted to engage over the tapered extremity 12 of the rest, as shown clearly in Fig. 2, and thereby hold 70 the lever in engagement with the rest. The drum 7 is equipped at the end remote from the rest 9 with a crank or other form of handle 12 by which it may be rotated and near said end is formed with an opening or 75 ratchet, indicated at 13, which may be engaged by a pawl or holding dog 14 pivoted upon the adjacent bearing 6 so that retrograde movement of the drum will be prevented. The drum is hollow as will be readily understood and the pawl has its end 80 sharply curved inwardly so that when the drum is rotated in one direction, the walls of the opening 13 will readily ride under the dog, but upon attempted movement of 85 the drum in the opposite direction the wall of the opening will engage the inner or concave surface of the hook end of the pawl or dog and the drum will be, consequently, held 90 against rotation. The drum is provided between the bearings 6 with a longitudinal slot 15, the function of which will presently appear, and at the end nearer the rest 9 and between the said rest and the adjacent bearing 6 the drum is constructed with a longitudinal slot 16 having its inner end communicating with a peripheral slot or opening 17 which forms the outlet terminal of an elliptical opening 18. The material of the drum is also cut away at the same end, as 95 indicated at 19, so as to provide a lip or hook 20 over which the wire may be engaged. At the upper extremity of the main plate or body 1, we provide a horn 21 which projects forwardly and upwardly over the 100 drum, the side edges converging, as shown at 22, so that the point 23 of the horn will be of small area and a loop of wire may be readily engaged over or released therefrom.

In splicing a broken fence wire by the 110

use of the tool which has been described, the anchoring foot 3 is driven into the ground, as shown clearly in Fig. 1, adjacent one end of the broken wire. The said end of the 5 wire is then doubled upon itself by hand so as to partly form a loop which, for convenience, will be described as the loop A and is so designated in Figs. 4 and 5 of the drawings. The wire which has been doubled 10 on itself to form the loop A is extended across the upper edge of the rest 9 and the loop engaged over the hook 20 after which the locking lever 10 is brought down upon the wire so as to hold both branches of the 15 same upon the rest 9, as clearly shown in Fig. 4. The drum is then rotated one or more times, preferably twice, so that the wire will be twisted about itself and the loop completed, this step being illustrated in Fig. 20 5 of the drawings. The loop thus completed is released from the hook 20 and the tool is then swung around upon its vertical longitudinal axis or removed from the ground and reanchored adjacent the opposite end of the broken wire. A loop B is formed in this second end of the broken wire in the same manner as the loop A was formed, the loop B being illustrated in Fig. 6. The loop B is then released from the tool 25 and the operator inserts a new length of wire through the drum 7 and doubles one end of this wire upon itself after having inserted it through the loop B, as shown in Fig. 7, the end of the shorter branch of this 30 wire being bent at a right angle to itself, as shown at 24, to extend through the opening 18 of the drum. The drum is then rotated so as to twist the branches of the loop C upon itself and thereby complete the loop 35 40 as well as unite it with the loop B. At this point it may be well to state that the length of wire from which the loop C is formed may be bent upon itself and engaged in the loop B before being inserted through the drum, and the particular sequence of these 45 two steps is immaterial. After the loop C has been completed, the loop A is engaged over the horn 21 and the tool, being withdrawn from the ground, is turned to a horizontal position so that the length of wire 50 upon which the loop A is formed will extend through the groove 2 of the tool and pass over the tailpiece 4. The free or unbent portion of the wire upon which the loop C is formed is then inserted through the loop A and into the slot 15 of the drum, as clearly shown in Fig. 8, after which the 55 drum is rotated so as to stretch the wire. After the wire has been drawn taut, the 60 tool is moved laterally to release the wire of the loop A from the tailpiece 4 and is then reversed, as shown in Fig. 9, so that the loop A will slip off the tip of the horn. The tool is then bodily passed around the 65 loops B and C as an axis so that the third

portion of wire between the drum and the loop A will be wrapped once or twice about itself. The end of said wire may then be withdrawn from the drum and wrapped manually about the stretched wire. 70

It is thought to be evident from the foregoing description, taken in connection with the accompanying drawings, that we have devised a very simple and efficient method of splicing fence wires and have produced 75 a tool by the use of which a broken fence wire may be very rapidly spliced and the spliced as well as the original lengths of wire stretched taut.

Having thus described our invention, what 80 is claimed as new is:

1. A tool for the purpose set forth, comprising means for holding the branches of a loop, and a drum constructed at one end to engage between the branches of the loop 85 whereby rotation of the drum about its own longitudinal axis will close the open end of the loop.

2. A tool for the purpose set forth comprising a main body, a drum rotatably 90 mounted upon the body and constructed at one end with a hook to engage a bent wire, and means carried by the body and disposed in spaced relation to the side of the same and the end of the drum to hold the said wire 95 during rotation of the drum.

3. A tool for the purpose set forth comprising a main plate, a bracket projecting laterally from the said plate and having a rest extending forwardly from its outer end, 100 means for clamping a wire loop on said rest, and a drum rotatably mounted upon the main plate and constructed at one end to engage the loop whereby rotation of the drum about its own longitudinal axis will twist 105 and close the loop.

4. A tool for the purpose set forth comprising a main plate, means on said plate for holding the branches of a loop and a drum rotatably mounted thereon, said drum 110 being constructed at one end with a hook adapted to engage within the loop, whereby rotation of the drum about its own longitudinal axis will twist and close the loop.

5. A tool for the purpose set forth comprising a main plate, and a drum rotatably mounted thereon, said drum being provided at one end with a wire-engaging hook and also constructed with a longitudinal slot 115 opening through the end of the drum and communicating with an opening formed through the wall thereof adjacent said end.

6. A tool for the purpose set forth comprising a main plate, and a drum rotatably mounted thereon and provided at one end with a circumferential slot forming a loop-engaging hook and also with a longitudinal slot having a lateral extension at its inner 125 end.

7. A tool for the purpose set forth com- 130

prising a main plate having a longitudinal wire-receiving groove in one face, wire-connecting means at one end of the plate, and a lateral tailpiece carried by the opposite end 5 of the plate to engage over the wire in said longitudinal groove.

8. A tool for the purpose set forth comprising a main plate having a central longitudinal groove, a tailpiece carried by one 10 end of the plate and having a dished portion to engage over a wire held in said groove, wire-stretching and coiling means mounted upon the opposite end of the plate, and means at the latter end of the plate for supporting the end of the wire in said groove 15

in engagement with a wire held in said stretching and coiling means.

9. A tool for the purpose set forth comprising a main plate, wire-coiling and stretching means mounted on the plate, a 20 horn projecting from the adjacent end of the plate over the said wire-coiling and stretching means, and a tailpiece to coöperate with the plate at a point remote from the horn.

25 In testimony whereof we affix our signatures.

CHARLES H. MATTHEWS. [L.S.]

JAY E. MATTHEWS. [L.S.]
